CanadaApplication June 30, 1941, Serial No. 400,526
In Canada June 3, 1941

1 Claim. (Cl. 263—41)

This invention relates to apparatus for drying lumber.

An object of the present invention is the provision of lumber drying apparatus which is a complete and independent unit.

Another object is the provision of lumber drying apparatus which does not require a trained and skilled operator.

Another object is the provision of lumber drying apparatus with a far greater drying capacity per cubic foot of space than have the kilns now in common use.

A further object is the provision of lumber drying apparatus which does not require steam and yet in which the lumber does not become case-hardened.

A further object is the provision of apparatus of the nature described of extremely simple and inexpensive construction.

In the lumber drying kilns now in common use, steam is employed to heat air in the kiln which is circulated through the piled lumber. This necessitates very expensive equipment. A basement is usually built under the kilns in which are placed great lengths of steam pipes and numerous fans for circulating air around these pipes and through the lumber, said fans and their bearings operating in very great heat.

This means the kiln must be located close to the boiler of the mill and as the mill is built around the boiler, the size and number of kilns that can be installed are very limited. One of the chief difficulties is that mills now operating cannot install new kilns because they have not the space available close to their boilers or their boilers have not the capacity to supply the steam for such a large demand when you consider that a kiln capable of accommodating about 100,000 feet of lumber requires enough steam to run a complete small mill.

Other disadvantages are that a steam engineer must always be available and the kilns must be in the charge of a specially trained operator, known as a kiln man, in order to operate them with any degree of success. These kilns have to be very well constructed and they must be operated at high temperatures to dry the lumber in a comparatively short time in order to make them pay. Furthermore, there is a great loss of heat since the heat is first transferred to water, converting it into steam, and then from the latter to the air to be circulated through the lumber. There is a great loss at each transference of the heat.

The chief object of this invention is to provide a lumber drying apparatus of very simple and in-

expensive construction operating at low temperatures, which does not require any steam and, therefore, may be set up at any desired point in relation to the mill. The need for drying lumber is becoming greater every day, as when shipping by rail, the freight per thousand feet of lumber is much less with dry lumber, and with ocean-borne lumber, it is a guarantee against discolouration and it is ready for use on arrival, thus commanding a higher price.

At the present time, the difficulty is that most mills have not the boiler capacity nor the space to put the boilers in that are necessary to do sufficient lumber drying while there are numerous small mills that cannot afford to install expensive dry kiln systems and, therefore, they are completely barred from this market.

This invention overcomes the above-noted disadvantages by providing a kiln in which the lumber is piled, means for directly heating and re-heating air, and means for circulating the heated air through the lumber in the kiln. This unit is complete and compact and it may be located at any desired point in relation to the mill. It is preferable to use sawdust for heating the air, thus utilizing to advantage a fuel which is ordinarily burned just to get rid of it. Neither a steam engineer nor a trained operator is required and it is not necessary to dry the lumber in a minimum of time. Consequently, it is possible to take much longer to dry the lumber, and as a result of this, the kiln may be of much lighter and inexpensive construction. The fuel economy is very great for there is considerable loss in heating water to make steam as compared with the direct application of heat to the drying air.

In the accompanying drawing,

Figure 1 is a side elevation of the drying apparatus,

Figure 2 is a plan view, partly in section, of the apparatus without any lumber piled therein,

Figure 3 is a vertical section taken on the line 3—3 of Figure 1,

Figure 4 is an enlarged section taken substantially on the line 4—4 of Figure 1.

Referring more particularly to the drawing, 10 is a drying chamber of any required shape, although it is preferably long and narrow, as shown. This chamber may be of any desired construction but, owing to the nature of this invention, it may be of comparatively light construction, while it has side walls 11 and 12, end walls 13 and 14, and a base 15.

The drying chamber is preferably open at its 55 top and is provided with a cover 16 removably

mounted thereon. This cover may be formed in one section or in several sections, as shown, depending upon the length of the drying chamber. It is also possible to have the cover permanently fixed on the chamber, in which case the end wall 13 would be in the form of a door. If the side walls 11 and 12 are lightly constructed, a plurality of heavy vertical supports 17, such as poles, may be provided for bracing said walls.

One or more valve arrangements 18 are provided adjacent the top of either or both the side walls 11 and 12. Each valve arrangement consists of a slide door 20 adapted removably to cover an opening 21 formed in the side walls.

Ducts 22 and 23 are mounted in the drying chamber at each side thereof and preferably adjacent its base 15, said ducts having a plurality of openings 24 formed therein. These ducts may progressively taper towards the end wall 13, as shown.

A drying chamber 25 located adjacent the end wall 14, preferably outside the heating chamber, is mounted on a base 26. A suitable heating unit is provided for heating the chamber 25 and in the preferred form of the invention, a sawdust burner unit 27 having a hopper 28, is used for this purpose. This burner unit is adapted to direct the products of combustion through a passage 30 extending longitudinally of the base 26, beneath the chamber 25, said passage curving upwardly at 31 to direct the products of combustion through a plurality of tubes 32 extending through the heating chamber. The tubes 32 discharge the products of combustion into a smoke header 33, from which a stack 34 projects upwardly.

A hot air pipe 35 connects the heating chamber 25 to the duct 22 and a return pipe 36 connects the duct 23 to a fan or blower 37 which, in turn, is connected to said heating chamber by a pipe 38. The pipe 35 communicates with the chamber 25 at the top towards the rear thereof while the pipe 38 communicates with said chamber adjacent its forward end. The fan or blower 37 is driven in any suitable manner, such as by an electric motor 40 having a pulley 41 which is connected by a belt 42 to a pulley 43 mounted on the shaft 44 of said fan.

Pipes 45 and 46 interconnect the hot air and return pipes 35 and 36. Control valves 47, 48, 50 and 51 are positioned in the pipes 35, 45, 46 and 36 respectively. Figure 4 is a section through one of these valves in partially open position. Each valve has a valve plate 52 which may be raised and lowered to open and close said valve. As the valves 47 and 51 are intended to be closed while the valves 48 and 50 are open and vice versa, there may be one valve plate 52 only for each set of valves. While the valves shown are suitable for the purpose, it is to be understood that any desired type of valve may be employed.

If desired, suitable means may be provided for supplying steam or atomized water to the hot air pipes 35 or at any other desired point in the system, should this prove necessary. An example of this is illustrated in Figure 2, in which a pipe 54, extending from a suitable source (not shown) is adapted to supply steam or water to one or more nozzles 55 located in the hot air pipe. A control valve 56 is provided in the pipe 54.

In use, the lumber is piled in the drying chamber 10 in any suitable manner. If the cover 16 is removable, and this is the preferred alternative, it is removed by means of a crane and the lumber lowered into the chamber in bundles. This lumber extends longitudinally of the chamber and it

is piled or bundled with spacers 53 extending transversely thereof. The advantage of this form of the invention, is that the lumber is usually carried from the mill in bundles by cranes and these are deposited at desired points. With this arrangement, these bundles may be picked up and deposited in the drying chamber without any special or extra piling.

If the roof is permanent, the lumber may be piled on small trucks and wheeled into the chamber, this being the practice now in common use. The difficulty is that the lumber has to be piled on the trucks, entailing extra and specialized labour.

15 Air circulates through the heating chamber 25, the drying chamber 10 and back to said heating chamber. The course of the air through this circuit depends upon the setting of the valves 47, 48, 50 and 51.

20 With the valves 48 and 50 closed and the valves 47 and 51 open, the hot air passes through the pipe 35 and the duct 22 into the drying chamber. This air moves transversely of the chamber through the piled lumber to absorb moisture therefrom. The air, now cooler, leaves the drying chamber and passes through the duct 23 and the pipe 36 back to the heating chamber. When the control valves are reversed, that is, the valves 47 and 51 are closed and the valves 48 and 50 are opened, the hot air passes through the pipes 35 and 45 and the duct 23 into the chamber, and the cooler air passes through the duct 22 and the pipes 46 and 36 back to the heating chamber.

If desired, natural circulation only may be used, 35 but it is preferable to employ a fan 37 to ensure a positive movement of the air.

The sawdust burner unit 27 directly heats the air in the chamber 25 so that a maximum amount of the heat generated is transferred to said air.

40 As the lumber dries, the air in the circuit becomes laden with the moisture extracted therefrom. Thus the natural moisture of the wood is utilized to prevent it from drying too rapidly, preventing checking and splitting, and it prevents 45 the lumber from becoming case-hardened, i.e., drier at the surface of each piece than in the interior thereof.

Should the air in the system become too moist, 50 one or more of the valve arrangements 18 may be partially or completely opened to permit some of the moisture-laden air to escape. If, on the other hand, the air becomes too dry, steam or atomized water may be injected thereinto through the nozzles 55.

55 The setting of the control valves 47, 48, 50 and 51, is arranged so that hot air flows into the drying chamber through one of the ducts for a time, and then the setting is changed to direct said hot air into the chamber through the opposite duct for an equal time. By alternating in this manner, the lumber is dried evenly on both sides thereof.

No skill is required to operate this apparatus. The hopper 28 of the sawdust burner unit needs 60 to be filled and the setting of the control valves needs to be changed at predetermined intervals.

The length of time necessary for drying the lumber depends upon the type of lumber and the degree of dryness required. With this apparatus, however, the drying may take longer than the kilns now in common use, but this is very desirable as far as quality of the finished products is concerned, and the cheapness of construction and operation of this apparatus eliminates the necessity of drying the lumber in the least pos-

sible time. The cheapness of operation and the completeness of operation and simplicity of this apparatus has the advantages that the drying chamber does not require any special construction and it may be of much lighter construction than the known kilns, since heat insulation is not required.

Various modifications may be made in this invention without departing from the spirit thereof or the scope of the claims and, therefore, the exact forms shown are to be taken as illustrative only and not in a limiting sense, and it is desired that only such limitations shall be placed thereon as are disclosed in the prior art or are set forth in the accompanying claim.

What I claim as my invention is:

Lumber drying apparatus comprising a drying chamber having openings for the escape of moisture near the upper part thereof, air ducts at opposite sides of the chamber adjacent to the base and extending longitudinally thereof, each duct being formed with openings in the top and being

gradually reduced in cross section from one end to the other, a heating unit comprising a fuel burning chamber, a heating chamber and a stack, the said heating chamber having a plurality of 5 tubes through which the products of combustion are designed to pass, pipes connecting the ducts to the heating chamber, one of the ducts opening at the upper part of the heating chamber and the other duct opening into the lower part of the heating chamber, a force draft fan operably associated with one of the ducts to effect circulation through the same, a pair of transverse interconnecting pipes connecting the two ducts, each of said transverse pipes having a valve 10 15 therein, control valves so arranged with respect to the transverse ducts that circulation of air may be caused to pass from one duct to the other in the drying chamber in either direction and means in one of the said ducts for adding moisture to the air.
